SNAP SWITCH

Filed Sept. 3, 1930

Fig. 1.

UNITED STATES PATENT OFFICE

PERCY G. SHAW, OF BRIDGEPORT, CONNECTICUT, ASSIGNOR TO GENERAL ELECTRIC COMPANY, A CORPORATION OF NEW YORK

SNAP SWITCH

Application filed September 3, 1930. Serial No. 479,442.

The present invention relates to small snap switches such as are used for controlling the circuit of electric lamps and other small electrical devices.

5 The object of the invention is the provision of an improved form of switch which is simple in construction, of small dimensions, reliable in operation, and of low manufacturing cost.

10 For a consideration of what I believe to be novel and my invention, attention is directed to the accompanying description and the claims appended thereto.

In the accompanying drawings which is 15 illustrative of my invention, Fig. 1 is a view of a switch partly in section and partly in elevation with the contacts in circuit closing relation; Fig. 2 is a similar view with the parts in open circuit relation; Fig. 3 is a 20 perspective view of the actuator; Fig. 4 is a perspective view of the contact carrying member; Fig. 5 is a perspective view of the supporting frame, and Fig. 6 is a perspective view of one of the movable contacts.

25 6 indicates a base which is made of porcelain, or other suitable insulating material, and 7 a cover for the switch parts which is also made of insulating material, whereby danger of shocks to the user is avoided. The base is of circular form and is provided with 30 openings 8 to receive screws for attaching the base to a suitable support. Formed integral with the base and rising above it, are two pillars 9 for supporting the cover 7 from 35 its under side. The central part of the base is provided with a cavity or recess 10 through which the lower end of a contact carrying member moves. The base is also provided with a pair of aligned surfaces or shoulders 40 11 upon which a supporting frame for the switch parts is mounted and held in place by screws 12. The frame is U-shaped and is made of one piece of thin sheet metal bent to shape as best shown in Fig. 5. It is provided with base portions or feet 13 which 45 rest on the shoulders 11 of the insulating base, and has two side portions 14, which rise vertically and terminate in overhanging portions of arms 15. In both of these portions 50 are holes 16 to receive the pivot 16^a for the

actuator. Each side member of the frame has two inclined or diverging walls 17, and the junction or apex of these walls forms a seat 18 for the pivot of the contact carrying member, the seats thus formed being directly below the pivot 16^a of the actuator. The frame is also provided with two downwardly inclined walls 19 on each side which act as stops to limit the movement of the contact carrying member. The walls 17 also act as 60 stops as shown in Fig. 1.

Referring now to Fig. 3, which shows the actuator, this comprises a thin sheet metal member having a head 20 that is enclosed at all points above the cover 7 by insulation 21, which latter is moulded around the head in any suitable manner. The total thickness of the insulation 21 is such that it fills the space between the frame portions 15, and is prevented thereby from moving sidewise. Formed integral with the head 20 is a curved and downwardly extending arm 22 which terminates in a hook 23. This hook serves a double function in that it forms an attaching means for the lower end of the spring 24, 75 Fig. 1, and also as a stop. In Fig. 1 it will be seen that the hook is in contact with the left-hand foot 13 of the frame and in Fig. 2 it is shown in contact with the right-hand foot 13 of the frame. From this it will appear 80 that the hook limits the movements of the actuator in both directions.

Referring to Fig. 4 which illustrates the contact carrying member, 25 indicates a sheet metal member which has a large central 85 opening through which a part of the U-shaped frame extends. It has top, bottom, and side walls and a pair of internal shoulders 26 which formed on the inner edges of the side walls rest on the seats 18 when the actuator swings from one of its positions to the other. The upper or top wall has an opening 27 to receive the upper end of the coiled tension spring 24. The member is caused to move with a snap action each time the axis of the spring 24 crosses a vertical plane passing through the pivot 16^a and seats 18. On account of the work which it has to do, the actuator 25 has to be made of metal of substantial thickness, so thick, in 95

fact, that it could not be bent or shaped to form contacts without danger of cracking the metal at each bend or corner. To obviate this difficulty, the member 25 is provided with two shoulders 28 on its lower side, and to each shoulder is secured a thin contact 29 which may be made of phosphor bronze or equivalent resilient material. To prevent the sides of the member 25 from spreading and also to hold the contacts in proper alignment, said sides are connected by the part 25^a. The contacts 29 may be secured to the actuating member in any suitable manner, as by a tenon 30 and solder 30^a, the latter being located on the back side of the member 25. Each contact 29 has a flat portion and an upturned end 31, and a rearwardly inclined portion 32. These contacts are designed to cooperate with a pair of fixed contacts 33, which are secured to the base 6 by screws 34, or other suitable means. Each of these contacts has a depending portion 35 which engages the moving contacts 31.

In a switch of this kind it is important that the meeting surfaces of the contacts be kept smooth and bright so as to establish good electrical connection. To do this the inclined portions 31 of the contacts are arranged to slide or wipe on the stationary contacts 35. This is accomplished by making the contacts 29 flexible, and also by so arranging the member 25 that when the parts 31 and 35 contact, the member 25 will move bodily in the direction of its length a short distance away from the seat 18, as best shown in Fig. 1. This is permitted by the particular mounting of the part 25, and the coil spring 24.

By reason of the overhanging portions 15 of the frame, the contact carrying member can be readily slipped into place and because the frame extends through the opening in the member 25 with small lateral clearances, the frame acts as a means to prevent the contact carrying member from shifting sidewise, and thus insures proper contact between the stationary and moving parts. The fact that the contact carrying member can be threaded over the frame means that the assembly operation is a simple one. By making the contacts 29 separate from the member 25, they can be made of the material best suited for the work at a very small expense. By mounting them so that they extend substantially at right angles to the plane of the member, they will in engaging the fixed contacts 35 do so with a wiping action. Due to the fact that the member 25 can move bodily in the direction of its length against the action of the spring 24, it follows that any inaccuracy in the positions of either the moving or stationary contacts is automatically compensated for. This freedom of movement of the member 25 is particularly useful to equalize the pressures exerted by

both moving contacts on the stationary contacts.

By reason of the arrangement described the switch is small for its duty and particularly in a direction perpendicular to the path of movement of the actuator. 70

What I claim as new and desire to secure by Letters Patent of the United States is:

1. In a snap switch, the combination of an insulating base having a supporting surface, 75 a U-shaped metal frame mounted thereon, said frame having overhanging arms at its upper end and seats below the arms, a contact carrying member having a large central opening within which the lower portion of the frame is located, said member having internal shoulders which form a pivot and engage the seats, flexible contacts secured to the lower edge of the member and extending substantially at right angles thereto, stationary contacts carried by the base which are engaged by the moving contacts as they move upwardly, a swinging actuator pivotally supported by said arms which has a single downwardly projecting element, and a spring connecting the upper end of the member with the lower end of the element, said spring causing the member and its contacts to move with a snap action and permitting the member to rise from its bearing seats to permit of a 95 wiping action of the moving and stationary contacts when the circuit is closed. 90

2. In a snap switch, the combination of an insulating base having a supporting surface, 100 a U-shaped metal frame having feet which rest on said surface, said frame having overhanging arms at its upper end and seats directly below the arms, a sheet metal member having shoulders which rest on said seats, flexible contacts secured to the lower end of the member which have up-turned ends, fixed contacts carried by the base having downwardly turned ends which are engaged by the flexible contacts on their upward movements, an actuator comprising a metal head 110 having a single downwardly extending curved element that terminates in a hook, said hook in its to-and-fro movements being arranged to strike the feet of the frame and act as a stop, an insulated cover for the head which is 115 located between said overhanging arms and is guided in its movements thereby, a pivot for the actuator which passes through the head and is supported by said arms, and a spring for moving said member with a snap 120 action which is connected at one end to the member and at the other end to said hook. 125

3. In a snap switch, the combination of an insulating base, a U-shaped pressed metal frame, the base of which is mounted on the insulating base, said frame having a pair of overhanging arms at its upper end, a seat below each arm formed at the apex of two diverging walls, said walls acting as stops for a movable member, a sheet metal movable 130

member having top, bottom, and side walls and a central opening within which a part of frame is located, internal shoulders formed on the inner edges of said side walls which 5 rest on the seats, spaced contacts secured to the lower end of the member which have up-turned flexible ends, fixed contacts having down-turned ends for engagement with the moving contacts, an actuator comprising a 10 pivoted head and a single depending curved element, the end of which is arranged to engage the base of the frame and act as a stop, and a spring which connects the curved element to said movable member for actuating 15 the latter.

In witness whereof, I have hereunto set my hand this 29th day of August, 1930.

PERCY G. SHAW.
